Primary Examiner — Leanne Was-Englehart

Assistant Examiner — Yelizaveta Y Masalimova

(57) **CLAIM**

The ornamental design for a sandal, as shown and described.

DESCRIPTION

FIG. 1 is a front, left and top perspective view of a sandal, showing my new design.

FIG. 2 is a top view thereof.

FIG. 3 is a bottom view thereof.

FIG. 4 is a right side view thereof.

FIG. 5 is a left side view thereof.

FIG. 6 is a rear view thereof.

FIG. 7 is a front view thereof.

FIG. 8 is a right and bottom perspective view thereof; and, FIG. 9 is an enlarged view of portion 9 shown in FIG. 8. The broken lines in the drawings depict portions of sandal that form no part of the claimed design. The dash dot dash lines in FIGS. 8 and 9 are for the purpose of illustrating the enlarged view indicators and form no part of the claimed design.

1 Claim, 9 Drawing Sheets
